UNITED STATES PATENT OFFICE.

CHRIS STADLER, OF MENOMINEE, MICHIGAN.

NECK-YOKE.

SPECIFICATION forming part of Letters Patent No. 726,585, dated April 28, 1903.

Application filed March 26, 1902. Serial No. 100,131. (No model.)

To all whom it may concern:

Be it known that I, CHRIS STADLER, a citizen of the United States, residing at Menominee, in the county of Menominee and State of Michigan, have invented a new and useful 5 Neck-Yoke, of which the following is a specification.

My invention relates to improvements in neck-yokes in which a pole-strap acts in conjunction with the guide-wheel, which is fastened to the head of the neck-yoke by a link; and the object of my invention is to provide a means by which the pole-strap can play over a wheel, obviating the strain and frequent 15 breakage of the strap and the jerking of the neck of the animal harnessed. I attain this object by the mechanism illustrated in the accompanying drawings, in which—

Figure 1 is a detailed view in perspective 20 of the entire machine as it appears when attached to the neck-yoke. Fig. 2 is a vertical section of the guide-wheel with its bearings. Fig. 3 is a detailed view of the combined 25 guide-wheel and link. Fig. 4 is a view of the bearing on which the guide-wheel revolves. Fig. 5 is a view in perspective of the guide-wheel detached. Fig. 6 is an end view of the 30 guide-wheel detached. Fig. 7 is a detailed view in perspective of the ferrule attached to the neck-yoke.

Similar letters refer to similar parts throughout the several views.

The pole-strap *a* is ordinarily passed through a ring attached to the end of the neck-yoke *b* by the staple *c*; but in my invention 35 I pass it around the barrel *d* of the guide-wheel *e*, where it is guided and held in place by the flanges *f f*, which in turn are guided and held in place by the shoulders *g g* of the link *h*, the lower end of which is securely 40 fastened to the end of the neck-yoke *b* by the staple *c*, through which it freely oscillates. For greater durability the guide-wheel *e* is made to revolve on an axle *j*, which may be lubricated through an oil-hole *k* in the barrel 45 *d* of the guide-wheel *e*, and the shoulders *g g* prevent the pole-strap *a* from fouling with the flanges *f f* of the guide-wheel *e*.

What I claim as my invention, and desire to secure by Letters Patent, is—

The combination in a neck-yoke, of a guide-wheel revolving upon an axle and guarded by shoulders with a link by which it is also securely attached to the neck-yoke by a staple, through which the link passes, substantially 55 as set forth and for the purposes specified.

In testimony whereof I affix my signature in presence of two witnesses.

CHRIS STADLER.
